RING SPINNING AND ANALOGOUS MACHINE

Application filed September 30, 1931, Serial No. 566,144, and in Great Britain February 11, 1931.

This invention relates to ring spinning and analogous machines, and it has for its chief object to enable larger packages, in either cop, tube or spool formation, to be produced than is possible with existing machines; another object of the invention being to preserve the most perfect spinning and building conditions obtainable throughout each spin or the like.

10 The invention is designed to meet the demand in the textile industry for greater weight and yardage of yarn built in cop, tube or spool shape, and to overcome the difficulties entailed by the necessity for employing cops, tubes or spools of much greater length than usual.

15 These difficulties are manifested differently according to the type of machine under consideration.

20 For instance, in a machine having a stationary spindle rail and a movable ring rail the shortening of the "balloon" of the yarn as the ring rail rises decreases the drag on the yarn and tends to produce soft-nosed 25 cops or the like; whereas, on the other hand, in a machine having a movable spindle rail and a stationary ring rail, the length of the "balloon" of the yarn remains constant and produces the maximum "balloon" drag 30 throughout the spin to which there is also added the frictional resistance due to loss of lubrication between the traveller and the ring, causing additional drag to the yarn.

35 Accordingly, a ring spinning or analogous machine is so constructed that at a certain point in the building of the package the spindle rail, together with the ring rail and builder mechanism, are lowered, at the same rate of speed as the ring rail traverses, without interruption of the relative movement of the ring rail, and in such manner that the ballooning of the yarn is maintained at the correct length for ideal spinning conditions throughout the complete 40 building operation of the package, that is to say, the balloon is shortened, as the spinning proceeds, up to the minimum length for efficient spinning conditions and is maintained at that length for the remainder of 45 the building operation.

The means controlling the movement of the ring rail are anchored to the spindle rail and the builder mechanism is constructed so as to permit the chain rod to have vertical movement and at the same time to receive the ordinary building motion; the spindle rail being so controlled that it remains stationary during a portion of the building operation and is lowered during the remainder.

50 According to one constructional embodiment of the invention, a ring spinning machine has a movable spindle rail and a movable ring rail, the lifter spindles supporting the ring rail passing through the spindle rail 55 and being connected to the chain rod by the usual dogs from which chains extend over pulleys carried by a plate supported by brackets which depend from and are secured to the spindle rail instead of to the framework of the machine.

55 The builder motion is provided with a rod end iron which is so constructed or arranged as to permit the chain rod to have a certain amount of vertical movement without prejudice to the building action.

60 The spindle rail is carried by lifter spindles whereof the dogs are each connected by a chain to a stationary shaft, each chain passing over a scroll secured to a rotary shaft 65 actuated, through suitable change gearing, 70 by the screw of the builder motion.

75 The above embodiment of the invention is illustrated by way of example in the accompanying drawings, wherein Figure 1 is a vertical section of part of a ring spinning frame illustrating only so much as to show the arrangement of the lifter spindle and chain rod according to the invention.

80 Figure 2 is also a vertical section of part 85 of the frame to show the attachment for lowering the spindle rail.

85 Figure 3 is a sectional plan view of part of the left-hand end of the frame, again showing only so much of the mechanism as is requisite for the understanding of the invention, Figure 4 is a front elevation of the same part of the frame, and Figure 5 is a diagrammatic view of certain gearing.

90 Referring to Figures 1 and 4, 1 is a verti- 100

cally movable spindle rail and 2 is a vertically movable ring rail carrying rings 3 upon each of which is the usual traveller 4. The spindles (not shown) are driven by whorls 5 and carry spools such as 6.

The ring rail 2 is supported upon lifter spindles 7 at the upper end of each of which is a cross-head 8, the lifter spindles 7 passing through apertures in the spindle rail 1 and each having at its foot a dog such as 9 connected by means of a chain 10 to the chain rod 11, each chain 10 passing by way of jockey pulleys to and over a pulley 12 mounted on a pulley plate 13 which is attached to the spindle rail 1 by brackets such as 14 depending from said spindle rail and bolted thereto at 15.

Referring now to Figures 2 and 3, the spindle rail 1 is carried by the lifter spindles 20 at the foot of each of which is a dog such as 17 to which is attached one end of a chain 18 whereof the other end is secured to a collar 18a fast on a stud 22 mounted suitably on a fixed part of the frame.

From the point of its attachment to said collar 18a, each chain 18 first passes over a scroll or spirally grooved roller 19 secured upon a continuous rotary shaft 20 and then each of said chains 18 passes over a guide pulley 21 also mounted upon the aforesaid stud 22 and thence to the dog 17.

23 is the rod end iron, the contact face 23a of which is so shaped as to permit the chain rod 11 to have a certain amount of vertical movement in addition to its normal longitudinal movement, said chain rod 11 being forked at its end to accommodate a roller 24 which contacts with the face 23a of said rod end iron 23.

40 The aforesaid continuous shaft 20 receives rotation through the medium of the builder-motion gearing 25, 26, 27 and the gear wheel 29.

25 is the driving wheel mounted on the sleeve 25a on the screw shaft 25b.

The gear wheels 26 and 27 are mounted on stud 28 (see Fig. 5) which is carried suitably by the frame end, and the gear wheel 29 is carried by the continuous shaft 20.

50 During the first half of the building operation the scrolls 19 rotating within the bights or loops of the respective chains 18 are so designed as to maintain the effective length of each chain 18 constant, but, during the remainder of the building operation gradually to lengthen each chain 18 thus lowering the spindle rail 1 and preventing the balloon of the yarn from becoming too short.

60 It will therefore be apparent that, by means of the above described apparatus, if the ring rail 2 is, say 4 inches higher than the spindle rail 1 at the commencement of the building operation, and if 10 inch spools 35 are being built, when the build is complet-

ed the ring rail 2 will be 14 inches higher than the spindle rail 1. When the building operation commences, the spindle rail 1 is in the normal position where it remains until the ring rail 2 is, say, 9 inches higher, that is to say half way, at which point the scrolls 19 commence to cause the spindle rail 1 to lower at exactly the same rate of speed as the ring rail 2 is traversing and without interruption of the relative movement of the ring rail 2.

10 In this manner the difficulties incidental to the building of the larger packages referred to above are overcome and the best conditions for spinning, twisting or the like 80 are maintained throughout the build.

What we claim is:

1. In ring spinning and analogous machines including a spindle rail, spindles carried by said spindle rail, a ring rail, rings carried by said ring rail, a builder motion having a rod end iron, and a chain rod actuated by said builder motion through said rod end iron, said spindle rail and said ring rail both being movable vertically; means controlling the movement of said ring rail suspended from said movable spindle rail, and means controlling said spindle rail so as at a certain point in the operation of said builder motion, to lower said spindle rail together with the ring rail and chain rod at the same rate of speed as said builder motion traverses said ring rail.

90 2. In ring spinning and analogous machines including a spindle rail, spindles carried by said spindle rail, a ring rail, rings carried by said ring rail, a builder motion having a rod end iron, and a chain rod actuated by said builder motion through said rod end iron, said spindle rail and said ring rail both being movable vertically; lifter spindles supporting said ring rail, said lifter spindles being supported by chains from said movable spindle rail, and means controlling said spindle rail so as, at a certain point in the operation of said builder motion, to lower said spindle rail together with the ring rail and chain rod at the same rate of speed as said builder motion traverses said ring rail.

100 3. In ring spinning and analogous machines including a spindle rail, spindles carried by said spindle rail, a ring rail, rings carried by said ring rail, a builder motion having a rod end iron, and a chain rod actuated by said builder motion through said rod end iron; said spindle rail and said ring rail both being movable vertically; lifter spindles supporting said ring rail, said lifter spindles passing through said spindle rail and being connected by chains to said chain rod, each of said chains being engaged by a pulley adjacent said chain rod, said pulley being supported by said spindle rail, and means controlling said spindle rail so as at 110 120 125 130

a certain point in the operation of said builder motion, to lower said spindle rail together with the ring rail and chain rod at the same rate of speed as said builder motion traverses said ring rail.

4. In ring spinning and analogous machines including a spindle rail, spindles carried by said spindle rail, a ring rail, rings carried by said ring rail, a builder motion having a rod end iron, and a chain rod actuated by said builder motion through said rod end iron; said spindle rail and said ring rail both being movable vertically; lifter spindles supporting said ring rail, said lifter spindles being suspended by chains from said movable spindle rail, lifter spindles supporting said spindle rail, said spindle rail lifter spindles being suspended by chains passing over spirally grooved pulleys, and means controlled by said building motion to rotate said pulleys so as, at a certain point in the operation of said builder motion, to lower said spindle rail together with said ring rail and chain rod at the same rate of speed as said builder motion traverses said ring rail.

5. In ring spinning and analogous machines including a spindle rail, spindles carried by said spindle rail, a ring rail, rings carried by said ring rail, a builder motion having a rod end iron, and a chain rod actuated by said builder motion through said rod end iron; said spindle rail and said ring rail both being movable vertically; in combination, means suspended from said spindle rail for controlling the movement of said ring rail, a rod end iron constructed so as to engage said chain rod when the latter has vertical movement as well as the normal building movement, and means controlling said spindle rail to cause it to remain stationary during a portion of the operation of said builder motion and to cause said spindle rail to be lowered during the remainder of said operation.

In testimony whereof they affix their signatures.

WILLIAM PRINCE-SMITH.
DAVID WATERHOUSE.
